PROCESS OF MAKING FOOTWEAR HOOKS

Adalberto Steinberg and Alfredo Cavadini,
Milan, ItalyApplication February 15, 1950, Serial No. 144,264
In Italy February 17, 1949

1 Claim. (Cl. 113—116)

1

The present invention relates to hook structures for shoes and similar footwear.

It is one of the objects of the present invention to provide means overcoming certain disadvantages observed when hooks are applied to footwear, which hooks generally permit snow and water to pass through an opening provided in the hook so as to penetrate the socks or the stockings of the wearer.

It is a further object of the present invention to provide means facilitating a simplified and effective process of shaping the hook from a single blank of material, and simultaneously closing of the hook opening in order to avoid passage of water or any moisture from the outside thereinto.

Yet a further object of the present invention is to provide means affording the production of sturdy hook structures in inexpensive and efficient bending operations.

These and other objects will appear from the ensuing specification, reference being had to the attached drawing in which some embodiments of the invention are illustrated.

Figs. 1a, 2a, 3a and 4a show schematically four elevational views of differently finished hooks made in accordance with the invention;

Figs. 1-4 illustrate four different top plan views of a blank of sheet material from which the respective hooks of Figs. 1a, 2a, 3a and 4a are manufactured;

Figs. 5, 5' and 5'' show, respectively, three different blanks in top plan views and further modified;

Fig. 6 illustrates still another top plan view of a blank made in accordance with the invention;

Figs. 7 and 8 illustrate elevational views, respectively, of hooks manufactured from the blanks seen in Figs. 5 and 6;

Fig. 9 shows still another embodiment of the invention in the form of a blank from which a hook with rounded edges and closed shank opening may be obtained;

Fig. 10 is a side elevational view of the hook made from the blank illustrated in Fig. 9;

Fig. 11 is a top plan view of the hook seen in any of Figs. 1a or 2a or 3a.

According to the embodiment represented in Fig. 1 blank 1 is punched out or struck out from a suitable piece of material having a hole 2 and a tubular member or shank 3. The upper part of hole 2 is closed by means of a little disk 5, secured for instance by dovetail, to perfectly seal hole 2. Blank 1 is then bent over with its part 4 so as to obtain the shape of the hook as represented in Fig. 1a. The hook is thus ready for application to the upper of a leather shoe, the same being ac-

complished in the conventional manner. In the embodiment according to Figs. 2 and 2a, blank 1 includes an end portion 6 opposite end portion 4 to thereby obtain the hook. Upon shank 3 being obtained by a drawing operation end 6 is then bent over the open end of the shank 3, thus closing it. Thereafter the usual bending operation is performed for obtaining the upper part of hook 4.

Figs. 3 and 3a represent a further embodiment in which extension 7, though being shorter than end 4 of elongated sheet metal blank 1, is longer than former end 6 so that besides closing and sealing opening 2, it contributes to reinforcing of the inner surface of the hook, upon completion of bending operations.

In Figs. 4 and 4a, extension 8 is longer than portion 4 so that, upon being bent over opening 2, it extends further to reach the end of part 4, on which it is turned back, thus forming a fixing point 9 that is anchored at the end of the very hook, to thereby bring about a higher elastic resistance. This is all apparent from the two walls, adjacent and interfixed together, that can be seen in Fig. 3a.

According to Figs. 5, 5', 5'' and 7, blank 1 presents, in respect to the conventional blanks, an enlarged portion 10, at opening 2 obtained through an embossing operation, while the opposite end 4 is destined to form the hook.

Opening 2 of the shank 3 is closed by means of a small disk as above explained in Figs. 1 and 1a. After having dovetailed said small disk, the enlarged portions 10 are bent inwardly as shown at Fig. 5' in 10', or outwardly as represented in Fig. 5'', at 10'', and successively the blank is bent so as to obtain the hook shape as represented in Fig. 7.

In this way there is obtained a perfect rounding off of the curved portion of the hook, with which the string is in contact, thus avoiding as much as possible any undue wear of the lace or string.

In Figs. 6 to 8 there is represented a further embodiment, except that the enlarged portion 11 is enlarged to fit the enlarged end portion 4, so that said enlargement 11, besides rounding off the edges, constitutes a reinforcement of the whole top portion 4 of the hook. The above mentioned enlargement may also be applied to the other embodiment represented in Figs. 1 to 4, showing the extension of blank 1 that closes opening 2 of shank 3.

In Figs. 9 and 10 there is represented another embodiment forming a modification of Figs. 4 and 4a, wherein however the opening 2 is dis-

posed at the end of blank 1, which is approximately twice as long as usual.

About midway of the blank, there is arranged an enlargement 14 which, upon the hook being finished, constitutes the upper wide portion of the very hook and between said enlargement 14 and terminal end 12 there is disposed an enlargement 10 for the rounding off of the edges. Further on, said end 12 there is provided a cup-shaped recess 13. The way of obtaining this hook is as follows: Blank 1 is first bent along dotted line 15 so that recess 13 be brought over hole 2, to close same. Upon the blank being fixed in this position, extensions 10 are bent, either inwardly or outwardly, so as to round off the edges and the hook is then formed, which is strengthened with rounded edges and with the shank mouth closed.

Of course other ways or embodiments could be devised by adapting the types of enlargements 10 or 11 to the several blanks of Figs. 1 to 4 without departing from the spirit of the present invention.

It can thus be seen that there has been provided according to the invention a novel process of manufacturing hook-shaped articles from a substantially flat and elongated blank of sheet material, comprising the steps of first deep-drawing at a location of said blank intermediate opposite ends thereof to thereby obtain an open-ended tubular part integral with and extending from the upper surface through the lower surface of said blank and substantially below the latter at said location, bending a portion adjacent one of said ends of said blank so that said portion overlies, extends beyond and is in intimate contact with said tubular part to thereby close the adjacent open end thereof, and then shaping the remainder of said portion of said one end and the opposite end of said blank so as to extend same from said tubular part in hook-shaped fashion to a location above said tubular part, with said remainder of said portion of said one end in face-to-face contact with the inner surface of said opposite end of said blank.

Having thus described the invention, what is claimed as new and desired to be secured by Letters Patent, is:

The process of manufacturing hook-shaped

articles from a substantially flat and elongated blank of sheet material, comprising the steps of first deep-drawing at a location of said blank intermediate opposite ends thereof to thereby obtain an open-ended tubular part integral with and extending from the upper surface through the lower surface of said blank and substantially below the latter at said location, bending a portion adjacent one of said ends of said blank so that said portion overlies, extends beyond and is in intimate contact with said tubular part to thereby close the adjacent open end thereof, and then shaping the remainder of said portion of said one end and the opposite end of said blank so as to extend same from said tubular part in hook-shaped fashion to a location above said tubular part, with said remainder of said portion of said one end in face-to-face contact with the inner surface of said opposite end of said blank.

ADALBERTO STEINBERG.
